Application filed February 17, 1899. Serial No. 705,902. Term of patent 3½ years.

To all whom it may concern:

Be it known that I, NELSON SANFORD STEWART, a citizen of the United States, residing at Amsterdam, in the county of Montgomery and State of New York, have invented and produced a new and original Design to be Worked into or upon Carpeting or Similar Fabrics; and I do hereby declare that the drawing accompanying this specification gives and conveys to any one skilled in the art of carpet-weaving a clear understanding of the same that is sufficient to enable such person to use my invention.

The said drawing is a face view of the carpet embodying my design, which consists of scrolls in the renaissance style; also, flowers and leaves arranged and treated as shown in the said drawing.

What I claim, and desire to secure by Letters Patent, is—
